SHELF OR RACK SUITABLE FOR
REFRIGERATORS OR THE LIKEBeryl L. McArdle, Battle Creek, Mich., assignor
to United Steel and Wire Company, Battle
Creek, Mich., a corporation of Michigan

Application September 13, 1939, Serial No. 294,602

8 Claims. (Cl. 211—153)

The main objects of this invention are:

First, to provide an improved shelf suitable for refrigerators or the like which is strong and rigid, and at the same time graceful and highly ornamental in appearance.

Second, to provide a shelf for refrigerators and the like which may be slidably mounted on supporting ledges and is provided with buffer means for preventing the metal parts thereof from scraping the finished inner side walls of the refrigerator, such buffer means also constituting means for ornamenting the shelf.

Third, to provide a shelf of the character described in which the ornamental element may be readily varied in shape or color to meet or harmonize with other ornamentations of a refrigerator or the like.

Fourth, to provide a structure having these advantages which may be very economically produced.

Objects relating to details and economies of the invention will appear from the description to follow. The invention is defined and pointed out in the claims.

Preferred embodiments of the invention are illustrated in the accompanying drawings, in which:

Fig. 1 is a fragmentary front elevation of a preferred form or embodiment of my invention.

Fig. 2 is a fragmentary perspective view of the embodiment of my invention shown in Fig. 1.

Fig. 3 is an enlarged fragmentary view sectioned on line 3—3 of Figs. 1 and 4.

Fig. 4 is a fragmentary section on line 4—4 of Fig. 3.

Fig. 5 is a fragmentary view in section through the frame of a modified form or embodiment of my invention.

Fig. 6 is a fragmentary view sectioned on line 6—6 of Fig. 5.

Fig. 7 is a fragmentary view in section through the border frame of an embodiment of my invention in which the front member of the border frame is formed of parallel rod-like portions and the ornamental insert secured between the rod members.

Fig. 8 is a fragmentary view of an embodiment of my invention in which the ornamental non-metallic strip is sleeved upon one of a pair of border frame members.

Fig. 9 is a front perspective view of still another form or embodiment of my invention.

Fig. 10 is an enlarged fragmentary plan view showing structural details of the embodiment shown in Fig. 9.

Fig. 11 is a fragmentary view in section on line 11—11 of Fig. 10.

Fig. 12 is an embodiment of my invention in which the front border frame member is formed of a pair of rod-like members of rectangular section.

Fig. 13 is an embodiment similar to that of Fig. 12 in which there are a pair of outwardly facing longitudinal recesses receiving a pair of ornamental elements.

Fig. 14 is a fragmentary view of a border frame sectioned through the frame showing a still further modification embodying a pair of ornamental strips.

Fig. 15 is a fragmentary view of still another modification or adaptation of my invention.

In the embodiment of Figs. 1, 2, 3 and 4 the main border frame is formed of rods 19 to the front member 20 of which the supplemental member 22 is secured by welds 23 providing a composite front frame or frame member having an outwardly facing longitudinal slot, recess or channel 24 between members 20, 22 in which the insert or finishing strip 25 is positioned and secured by folding the end 27 thereof inwardly at the ends of the member 22 which extend around the corners of the frame. Additional securing clips may be provided but the plastic material preferably used is of a character that has considerable rigidity when cold. In this embodiment shown in Figs. 1 to 4, inclusive, the border frame presents a series of rounded surfaces, the intermediate surface being preferably of plastic material and contrasting with the surfaces of the members 20 and 22.

In the embodiment shown in Figs. 5 and 6 the frame member 19 is provided with a front portion 20 to which is secured the curved sheet metal member 28 so conformed as to coact with the part 20 in defining a front frame or frame member having the outwardly facing longitudinal slot, channel or recess 29 receiving the insert 30 corresponding in general to the insert 25. Bendable clips 31 are provided on the ends of the shelf for clamping the end portions 32 of the insert into the recess.

In the embodiment shown in Fig. 7 the frame member 19 has a supplemental member 33 corresponding to the member 22 secured thereto in spaced relation by means of the tie members 34 and, like the preceding embodiments in which a composite front frame member is involved, coacting with member 19 in defining said composite front frame having a slit extending therealong between the top and bottom sides thereof,

the insert 35 being inserted or clamped in said slot between the frame member 33 and the opposed coacting member 20.

In the embodiment shown in Fig. 8 the front border member 36 of the frame has a member 37 secured thereto as by spot welding at 38. The member 37 is of smaller diameter than the member 36 and has an ornamental sleeve 39 thereon, this sleeve being of plastic or suitable contrasting material.

In the embodiment shown in Figs. 9 to 11 the front border member 40 has rearwardly turned ends 41, the slot or channel 42 extending into these ends. The end members 43 of the frame are inwardly offset at 44 and secured by welding at 45 to the inner side of the member 40. The finishing strip or insert 46 in this embodiment is folded around the rearwardly curved ends of the member 40 as shown at 47, Figs. 9 and 11, and is secured thereto by means of suitable bendable clips 48, see Figs. 10 and 11.

In the foregoing description I employ the terms "slot," "channel" and "recess" interchangeably to designate the longitudinal ornamental strip-receiving way intermediate the top and bottom of the frame or border, whether the same is constituted by a pair of rod-like members suitably secured together in spaced relation or otherwise by welding, as in the embodiment of Figs. 1 to 4 for example, or whether it is constituted by a single integral member grooved medially of its top and bottom, as for example in the embodiment of Figs. 9, 10 and 11. So far as the concept of receiving the said strip is concerned, the two concepts are functionally the same. I therefore desire the terms to be so construed in the description and claims to follow, unless modified by further structural details.

In the embodiment of my invention shown in Fig. 12 the front border frame designated generally by the numeral 49 comprises a pair of coextensive rectangular bar members 50 secured together by the tie members 51 in spaced relation to provide a longitudinal slot, channel or recess 52 in which the finishing insert 53 is arranged.

In Fig. 13 the frame member is made up of three of the bar-like members 50 secured together by the tie member 54 corresponding to the tie member 51 providing two longitudinal slots, channels or recesses 52 for the inserts 53.

In the embodiment of my invention shown in Fig. 14 the front frame member 55 is provided with an outwardly facing slot or channel 56 to receive the insert 57, a sheet metal strip 58 being secured to the under side of the member 55 to provide a second outwardly facing slot or channel or recess 59 for a finishing strip 57.

The embodiment of my invention shown in Fig. 15 is quite similar to that shown in Figs. 1, 2, 3 and 4 in which the supplemental member 22 is secured to the front member 20 of the border frame 19 to provide a composite front frame or frame member between the top and bottom sides of which there is defined a slot or channel for the finishing strip 25. In this embodiment of Fig. 15 the wire slats or grid elements 60 are disposed with their ends between the members 20 and 22 and welded thereto as indicated at 61. The slat or grid members thus perform the double function of constituting weld elements, 70 avoiding the necessity of introducing welding lugs as shown at 23 in Fig. 3 and also as an effective means for securing the slats.

All of these embodiments provide for contrasting surfaces and very ornamental and effective 75

results can be secured in addition to the advantage of the finishing strip serving as a buffer.

I have illustrated and described my improvements in several embodiments thereof from which it is apparent that my invention is capable of a wide adaptation or application.

I claim:

1. In a structure of the class described, the combination with a border frame comprising a front member including a pair of rod-like members of circular section disposed in superimposed relation and spot-welded to one another at spaced points to provide an elongated outwardly facing longitudinal slot, grid elements secured to said frame, and a strip of material arranged in said slot to provide a contrasting ornament for said front member.

2. In a structure of the class described, the combination with a border frame comprising a front member including a pair of rod-like members disposed in superimposed relation and connected by transverse tie means to provide an elongated outwardly facing longitudinal slot, grid elements secured to said frame, and a strip of material arranged in said slot to provide a contrasting ornament for said front member.

3. In a structure of the class described, the combination with a border frame comprising a front member, of grid elements secured to said frame, said front frame member comprising a rod-like element, and a transversely curved member secured thereto and coacting therewith to provide an elongated outwardly facing longitudinal slot, and a strip of ornamental material arranged in said slot.

4. In a structure of the class described, the combination with a border frame comprising a front frame member, an auxiliary front member disposed below said front frame member, grid elements disposed between said front frame member and auxiliary member and welded thereto, said members coacting to provide an elongated outwardly facing slot between the top and bottom of the thus associated members extending longitudinally of the members, and an insert strip of material arranged in said slot to provide a contrasting ornament and to close the space between said front frame and auxiliary member and cover the ends of said grid members.

5. In a structure of the class described, the combination with a border frame comprising a front frame member, an auxiliary front member, said front frame member and auxiliary frame member being disposed in superimposed relation, grid elements disposed between said front frame member and auxiliary member and welded thereto, said members coacting to provide an elongated outwardly facing slot between the top and bottom of the thus associated members extending longitudinally of the members, and an insert strip of material arranged in said slot.

6. A shelf of the class described comprising a border frame comprising a front member having an elongated outwardly facing slot disposed between the top and bottom of said member and extending longitudinally thereof, the edges of the slot being outwardly rounded to present bead-like surfaces, grid elements disposed with their front ends abutting the inner side of the front member of the frame and welded thereto, and a strip of plastic material arranged within said outwardly facing slot to project slightly outwardly therefrom and constituting an ornamental beading between said bead-like surface.

7. A shelf of the class described comprising

a border frame and grid elements, the front member of the border frame having a pair of superposed rod-like elements and means for securing the same in superposed relation to provide an elongated outwardly facing slot extending longitudinally of said member, and an ornamental filler strip arranged within said outwardly facing slot.

8. In a shelf of the class described, the combination of a border frame comprising a front member having a pair of superposed, curved sur-

faced, rod-like elements defining therebetween an elongated outwardly facing slot between the top and bottom of the member and extending longitudinally thereof, tie members securing said elements in operative relation, grid elements secured to said frame, and a strip of material distinct from that of said member arranged in said slot to constitute a finishing element for said front frame member.

10

BERYL L. McARDLE.
